TELESCOPE

Joseph D. Kieffer, III, Rochester, and William M. Strom, Irondequoit, N. Y., assignors to Bausch & Lomb Optical Company, Rochester, N. Y., a corporation of New York

Application May 31, 1951, Serial No. 15,354

Term of patent 14 years

(Cl. D57—1)

To all whom it may concern:

Be it known that we, Joseph D. Kieffer, III, and William M. Strom, citizens of the United States, and residents, respectively, of Rochester and the town of Irondequoit, county of Monroe, and State of New York, have invented a new, original, and ornamental Design for a Telescope, of which the following is a specification, reference being had to the accompanying drawing, forming a part hereof.

Fig. 1 is a side elevational view of a telescope showing our new design.

Fig. 2 is an elevational view of one end thereof.

Fig. 3 is an elevational view of the other end thereof.

Fig. 4 is a perspective view thereof.

We claim:

The ornamental design for a telescope, substantially as shown.

JOSEPH D. KIEFFER, III.
WILLIAM M. STROM.
